UNITED STATES PATENT OFFICE.

SAMUEL PRICE STEVENSON, OF CHESTER, PENNSYLVANIA.

FASTENER FOR DOORS.

1,099,626.

Specification of Letters Patent.

Patented June 9, 1914.

Application filed July 15, 1912. Serial No. 709,338.

To all whom it may concern:

Be it known that I, SAMUEL PRICE STEVENSON, of Chester, in the county of Delaware and State of Pennsylvania, have 5 invented certain new and useful Improvements in Fasteners for Doors, whereof the following is a specification, reference being had to the accompanying drawings.

The invention relates more particularly to 10 fastening devices for doors, which include a latch, together with operating devices for releasing the latch from either side of the door.

An object of the invention is to provide a 15 latch-releasing mechanism which is simple in construction and wherein the parts may be readily manipulated with little or no binding action thereon.

A further object of the invention is to 20 provide a swinging door with a latch mechanism which includes releasing devices for the latch, which may be operated from either side of the door, and by a movement in the direction of the swing of the door.

In the drawings which show by way of 25 illustration one embodiment of the invention, Figure I, is a front view of a latch-operating mechanism having my improvements applied thereto. Fig. II, is a sectional view on the line II, II, of Fig. I. 30 Fig. III, is a sectional view on the line III, III, of Fig. I, and Figs. IV, and V, are sectional views showing the operating lever and the operating rod for the lever partly in elevation and partly in section, and in 35 different positions.

My improved fastener comprises a supporting plate 1, from which project lugs 2, 2. Mounted in the lugs 2, 2, so as to rotate freely therein is a shaft 3. This 40 shaft 3, is provided with a rigid arm 4, at one end thereof, which arm carries a latch roller 5. This latch roller 5, is adapted to engage a keeper 6. The front surface 7, of the keeper 6, is inclined away from the plane 45 of movement of the axis of the latch supporting shaft 3, as the parts approach one another in the closing of the door. The keeper is also provided with an inner surface 8, which co-operates with the latch roller 5, in firmly locking the door in closed position. This surface 8, is curved substantially about the axis of the shaft 3, as a center. The keeper 6, is carried by a supporting base plate 9, which is adjustably secured to the 55 frame of the door by bolts 10. A spiral spring 11, is wound about the shaft 3, and is secured at one end to a collar 12, carried

by the shaft 3, while the other end of the spring is secured to an arm 13, projecting from the supporting plate 1. This spring 60 normally tends to rotate the shaft so as to swing the latch roller 5, toward the inclined surface 7, and to carry the latch down the inclined surface 8, after the latch passes the nose of the keeper. For releasing purposes, 65 the shaft 3, supporting the latch is swung in the opposite direction by a lever 14, which is rigidly secured to the shaft by a pin 15. To provide for operating the fastener from the rear side of the door, this arm or lever 70 is provided with a vertical slot 16, into which projects the end of rod or bar 17. This rod extends through the door, and is mounted in suitable bearing plates. The opposite end of the rod is provided with a 75 knob 18, by which the rod may be moved longitudinally in the door. Said lever or arm 14, is formed with curved slots 19, which are located in the side walls of the central slot 16.

The rod 17, carries a cross pin 20, on which are mounted rollers 21, which engage the curved slots formed in the side walls of the arm or lever 14. These slots are curved, so that the line of pressure due to 85 the longitudinal movement of the rod is substantially at right angles to a tangent to the curve at the point of contact of the rollers carried by the rod with the curve. In other words the contacting surface of the 90 slot is substantially at right angles to the plane of travel of the rollers. In other words, when the parts are in the position shown in Fig. III, an endwise movement of the rod to release the latch will exert a force 95 against the arm 14, which is substantially at right angles to the curve of the slot at the point of contact between the roller and the slot. When the parts are moved to the position shown in Fig. IV, it will be noted 100 that this slot is so curved that the pressure is at this point substantially at right angles to a line tangential to the curve at the point of contact of the roller with the curve. The same is true when the parts are moved to the 105 position shown in Fig. V. By this construction of the slot, I am able to manipulate the arm or lever connected to the latch by a rod which moves in a straight line without any resulting lateral or binding strains 110 on the rod which would occur if said slot were straight and in a direction longitudinal of the arm.

The operation of my device is thought to

be obvious from the above description. The latch may be released by an outward pull on the arm or lever 14, and the spring will throw the latch to closing position. The 5 latch may also be released by a push on the knob 18, which will move the rod longitudinally in its supporting bearings without any binding therein, and will swing the latch-operating lever or arm about its axis, turning the shaft 3, so as to release the latch.

From the above description, it will be apparent that I have provided a latch mechanism wherein the latch may be released by a pull on the lever 14, and this pull is in the 10 direction required for opening the door. Likewise, when the door is opened from the opposite side, the latch is released by a push on the knob 18, and rod 17, which is also in the direction of movement of the door as 15 said door swings to open position. It will also be obvious from the above description, that I have provided a latch releasing mechanism, wherein the operating parts are not only moved for releasing the latch by a 20 force applied in the direction for opening the door, but also this force is applied at a point exceptionally close to the free edge of 25 the door.

While I have shown my latch releasing 30 devices as applied to one form of latch, it will be obvious that these releasing members operating as above noted, may be utilized in connection with other forms of latches.

It is obvious that minor changes in the 35 details of construction may be made, without departing from the spirit of the invention as set forth in the appended claims.

Having thus described my invention, I claim:

40 1. In a fastener for doors, the combination of a latch for holding the door closed, a spring for normally throwing the latch to locking position, and means for releasing said latch, including a swinging lever on one 45 side of said door, a push rod extending through the door, and connected to said lever, and devices for connecting the lever to the latch, whereby the movement of the lever in the direction for opening the door, 50 will release the latch.

2. In a fastener for doors, the combination of a latch for holding the door closed, a spring for normally throwing the latch to locking position, and means for releasing 55 said latch, including a swinging lever on one side of said door, a push rod extending through the door, means for connecting the push rod to the lever, and devices for connecting the lever to the latch, whereby the 60 movement of the lever in the direction for opening the door, will release the latch.

3. In a fastener for doors, the combination of a latch for holding the door closed, a

spring for normally throwing the latch to locking position, means for releasing said latch, including a swinging lever on one side of said door, a push rod extending through the door and connected to said lever, devices for connecting the lever to the latch, whereby the movement of the lever in the direction for opening the door will release the latch, said connection between the pusher rod and the lever including a curved slot 65 formed in said lever, and a roller carried by said rod, said slot being so curved that the longitudinal pressure of the rod against the lever is in a direction substantially at right angles to a tangent to the curve of the slot at the point of contact of the roller with the curve.

4. In a fastener for doors, the combination of a shaft adapted to rotate about an axis substantially parallel to the plane of the door, an arm, a latch pin carried by the arm, a stationary keeper having an inclined front 70 surface adapted to engage the latch pin, a spring normally tending to throw the arm of the shaft so as to hold the latch in engagement with the keeper, a lever for swinging said latch, so as to release the same from the 75 keeper, and a rod extending through the door and having a sliding connection with the lever, whereby a longitudinal movement of the rod will oscillate the lever to release the latch.

5. In a fastener for doors, the combination of a shaft adapted to rotate about an axis substantially parallel to the plane of the door, an arm, a latch roller carried by said arm, a stationary keeper having an inclined front surface adapted to engage the latch pin, a spring normally tending to throw the arm of the shaft so as to hold the latch pin in engagement with the keeper, a lever for swinging said latch, so as to release the same from the keeper, a rod extending through the door and having a sliding connection with the lever, whereby a longitudinal movement of the rod will oscillate the lever to release the latch, said sliding connection between the lever and rod including a curved slot formed in said lever and a roller carried by the rod and engaging said curved slot, said curved slot being so shaped that the longitudinal pressure of the rod against the lever is in a direction substantially at right angles to a tangent to the curve at the point of contact of the roller with the curve.

In testimony whereof, I have hereunto 120 signed my name at Philadelphia, Pennsylvania, this thirteenth day of July 1912.

SAMUEL PRICE STEVENSON.
